UNITED STATES PATENT OFFICE

HERMANN HEINICKE, OF DRESDEN, GERMANY

NAME PLATE

Application filed August 31, 1929, Serial No. 389,749, and in Germany July 12, 1928.

This invention relates to the devices by means of which on the spot name plates can be composed to indicate where water slides, fire plugs, tapping cocks, water seals and shutting valves in water and gas pipes, electric cables and the like are located.

Plates on which the numerals and characters can be interchanged have become known, such plates are however of cast iron, and blocks with numerals cast on are to be riveted on these plates. Such plates become of bad appearance after a very short time and they get rusty, so that the numerals and characters are difficult to read.

Plates have further become known the base portion of which consists of a sheet metal box having apertures in which the signs, stamped from sheet metal, are to be inserted and secured in position by a sliding plate on the back. Such plates can be coated only with enamel lacquer, but not with stove enamel, as the latter is too thick so that the characters and numerals no longer fit in the windows. The enamel is easily broken off at the inserting of the characters and numerals. Enamel lacquer is not light-proof nor weather-proof, so that the appearance of the plates suffers very soon and as water can filter through the fissures in the windows, the joints get rusty.

Enamelled signs do not allow of folding over the bent off ends on the rear side of the plate, as the enamel will peel off at the bending, so that not only the appearance of the plates is spoiled but the influences of the weather can more easily act on the plates.

The novelty of the invention consists in that every individual sign plate has extensions at the ends, designed to be inserted through narrow holes in the plates and to be held on the back of the plate by means of metal seals. The use of metal seals presents the advantage that the enamelled sign plates can be stamped in one piece, this being not possible when screws and nuts are used for fixing the numerals and characters. Instead

of enamelled base plates numerals and characters of weather-proof material may be used, for instance of aluminium, rustfree steel or the like. In this case the bent over or otherwise produced ends of the characters and numerals might be fixed by screw bolts and nuts or they might have slots through which on the rear side of the plate wedges are to be inserted. The use of weather-proof material presents further the advantage that it is no longer necessary to paint or coat the plates, numerals and characters.

An embodiment of the invention is illustrated by way of example in the accompanying drawing in which:

Fig. 1 shows a name plate in elevation.

Fig. 2 is a rear elevation of Fig. 1.

Fig. 3 is a cross section on line A—B of Fig. 1.

According to the invention a plate *a*, which has a number of apertures *b*, has to carry for instance the capital letter S, the numerals 200; 3.5; 18.1; the arrow *c* and the lead seals *e*. The sign plates are stamped, as shown in Fig. 9, together with the ends *d* in one piece, the front side of the sign plates being pressed so that it is of curved cross section, as shown in Figs. 7 and 8, and the ends *d* being bent at right angles to the rear. The sign plates and the plate *a* are then coated with stove enamel.

The signs are fixed on the plate *a* by passing the ends *d* through the apertures *b* of the plate *a*, whereupon from the rear of the plate *a* seals *e* of lead or similar soft metal are placed over the projecting ends *d*. These lead or other seals are then compressed so that the material fills the indentations *f* of the ends *d*, whereby the sign plates are rigidly connected with the plate *a*. By the use of soft metal seals *e* cracking off of the stove enamel on the sign plates and on the plate at the compressing is precluded.

I claim:

1. A name plate comprising in combina-

tion a plate having several apertures, sign plates each having an extension at each end bent at right angles to the body thereof, said ends having indentations and being inserted through the corresponding apertures of said plate, and lead seals compressed over the extensions of said signs at the rear of the plate so that the metal of the seals fills the indentations of said ends to rigidly connect said sign plates with said apertured plate.

2. A name plate as specified in claim 1, comprising in combination a plate and sign plates, both of weather proof material and with a coating of stove enamel.

16 In testimony whereof I affix my signature.
HERMANN HEINICKE.
